UNITED STATES PATENT OFFICE.

FREDERICK J. LUDWICK, OF PHILADELPHIA, PENNSYLVANIA.

STAIR TREAD, PAD, OR LINING.

1,320,016.

Specification of Letters Patent.

Patented Oct. 28, 1919.

Application filed March 7, 1919. Serial No. 281,173.

To all whom it may concern:

Be it known that I, FREDERICK J. LUDWICK, a citizen of the United States, residing at Philadelphia, in the county of Philadelphia, State of Pennsylvania, have invented a new and useful Stair Tread, Pad, or Lining, of which the following is a specification.

My invention consists of a stair tread, 10 pad or lining composed of a body of cork in the condition of granules or shavings formed into a comparatively solid and homogeneous mass of cork which is pliable, resilient, strong and durable in its nature, 15 and possessing smooth and uniform surfaces, a reinforcement in the form of a mesh of wire or equivalent with which the adjacent portions of the body are joined, the same adding strength to the body and preventing 20 disintegration of the same, and a guard within the body at the nose portion thereof adapted to prevent chipping of said portion and adding elasticity thereto.

It consists finally of an air cushion in the 25 underside of said body adapted to permit a slight sinkage of said body when occupied adding additional elasticity or resiliency to the latter.

The invention is satisfactorily illustrated 30 in the accompanying drawing but the important instrumentalities thereof may be varied, and so it is to be understood that the invention is not limited to the specific details shown and described, as long as they 35 are within the spirit or scope of the claims.

Figure 1 represents a perspective view of a stair tread, pad or lining embodying my invention.

Fig. 2 represents a longitudinal section 40 thereof on line 2—2 Fig. 1.

Fig. 3 represents a transverse section thereof on the line 3—3 Fig. 1.

Fig. 4 represents a perspective view of a portion thereof partly broken away.

Similar numerals of reference indicate 45 corresponding parts in the figures.

Referring to the drawings.

1 designates the body of the tread, pad or lining, the same being composed of a 50 mass of cork in granulated or shavings form within which mass is the reinforce 2 consisting of a piece of woven wire or mesh-like material which extends in the longitudinal direction of the mass. The fore part of said

reinforce is turned upwardly forming the 55 elbow 3 which is salient from the reinforce and occupies the nose portion of the tread, pad or lining. Said reinforce and elbow are embedded in the mass. Some of the mass is placed in a mold, the reinforce and elbow 60 located in position thereon, and the final quantity of the mass applied, thus completing the body of the article. The body is then heated and compressed whereby its 65 shape is produced, and owing to the oil in the cork causes the granules or shavings to adhere to each other, some of which pass through the interstices of the mesh and clenches therewith, producing a homogeneous 70 compact and solid mass, resulting in the formation of the tread, pad or lining of pliable, resilient, strong and durable 75 nature with smooth and uniform surfaces. The nose portion of the article is sustained upwardly additionally reinforced and rendered 80 resilient by the elbow 3 especially where the feet primarily strike the same in the occupation of the article and so said nose portion is guarded against chipping, fracture and disintegration.

In the underside of the body 1 is the recess 4 which provides an air chamber or cushion therein permitting sinkage of the body whereby the latter when occupied has additional resiliency imparted to it, and the 85 tread, pad or lining is rendered more elastic in its nature.

It is evident that the article requires no inclosure such as a sack or case of fibrous material, it being complete of itself, and if 90 desired, the mass of cork may be colored and the surface of the article may be ornamented by designs thereon in any suitable manner.

Having thus described my invention what I claim as new and desire to secure by Letters 95 Patent, is:—

1. A tread, pad or lining of the character stated composed of a homogeneous body of compressed granules or shavings of cork, and a sustaining guard for the nose portion 100 of the body embedded in the said portion.

2. A tread, pad or lining of the character stated composed of a body of compressed granules or shavings of cork, a reinforcement in said body, and a sustaining guard 150 for the nose portion of said body adding resiliency to said portion and further reinforcing the same.

3. A tread, pad or lining of the character stated composed of a body of compressed granules or shavings of cork, a reinforcement of mesh-like material embedded in said body, and an elbow of said material in the nose portion of said body.

4. A tread, pad or lining of the character stated composed of a homogeneous body of compressed granules or shavings of cork, a 10 and an air cushion in the underside of said body.

5. A tread, pad or lining of the character stated composed of a homogeneous body of compressed granules or shavings of cork, a 15 reinforce of mesh-like material embedded in

said body, and an air cushion in the underside of said body.

6. A tread, pad or lining of the character stated composed of a homogeneous body of compressed granules or shavings of cork, a reinforce of mesh-like material embedded in said body, an elbow extending from said reinforce into the nose portion of said body and likewise embedded therein, and an air cushion in the underside of said body. 20

FREDK. J. LUDWICK.
